BIRDPREOFING

Julius Stanley Peles, New York, N. Y.

Application November 3, 1944, Serial No. 561,653

3 Claims. (Cl. 20—1)

1

This invention relates to improvements in bird-proofing. Such material is applied to buildings or other structures which are infested with birds to prevent them from alighting thereon. The present invention relates to the type of birdproofing of which the protecting elements are in the form of upstanding rigid wires. In that type of structure these protecting elements are usually interconnected by other wires and the assembly of the parts thereof is difficult and expensive and the resultant structure is flimsy and short lived. The object of the present invention is to provide a durable construction which is free of the aforesaid and other objectionable features inherent in former devices and which is inexpensive to make and easy to apply to desired structures.

These and other objects of the invention will appear in the following specification and its novel features will be set forth in the appended claims.

Referring to the drawings:

Figure 1 is a sectional elevation of a structure which is made according to and embodies my invention. In this figure the parts of the device are separated somewhat in order to illustrate the construction more clearly.

Fig. 2 is a transverse sectional elevation;

Fig. 3 is an inverted plan view on an enlarged scale of the structure shown in Fig. 1, with parts broken away and other parts shown in section;

Fig. 4 is a transverse sectional elevation of a modified form of the device;

Another modification is shown in transverse sectional elevation in Fig. 5;

Fig. 6 is an inverted plan view of the arrangement shown in Fig. 5;

Fig. 7 is an elevation of a further modification;

Fig. 8 is a transverse sectional elevation and Fig. 9 a plan view of the construction shown in Fig. 7;

Fig. 10 is a plan view of a still further modification;

Fig. 11 is a modification of the arrangement shown in Fig. 5;

Fig. 12 is a modification of a part of the arrangement shown in Fig. 11, and

Fig. 13 and 14 are modified forms of protective elements.

Referring first to Figs. 1-3, 11 and 11A designate a plurality of similar protective elements which may be made of wire, each of which comprises a pair of parallel shafts 12, 12A of unequal lengths interconnected at one end by integral tie portions 14, 14A also of different lengths, preferably forming right angles with the shafts. From the other ends of the tie portions 14, 14A shafts

2

13, 13A extend upwardly. As shown in Fig. 1, the shafts 13 are shorter than the shafts 12 of the same protective units; the shafts 12A are longer than the shafts 12, and the shafts 13 are shorter than the shafts 12, but longer than the shafts 13. The upper ends of the longer shafts 12, 12A are bent over to form loops 15, 15A for the purpose of preventing injury to the birds. The shafts are made of different lengths in order to ward off birds of different sizes.

20 is a base constructed of any desired material such for example as sheet metal. This is a longitudinally continuous member which, as clearly shown in Fig. 3, is in cross-section, in the form of an inverted trough with flanges extending outwardly from its open sides. The upper part 21 of this base is flat and in it are two rows of longitudinally spaced perforations 22 and 23 slightly offset transversely from each other through which the shafts 12, 12A and 13, 13A of the protective elements pass. When the upper ends of the shafts 12 are bent over to form loops 15, the perforations through which they pass are in the form of longitudinally disposed slots. The other perforations are circular.

25 Sides 24, 25 extend downwardly from the part 21. These sides converge inwardly, as shown, and tend to hold the protective elements in place. Flanges 26, 27 of unequal width extend outwardly and downwardly from the lower edges of these sides. Longitudinally spaced holes are provided in the wider flanges 27 for the reception of screws 28 or other holding means for securing the device to a desired structure. This forces the lower edges of the sides 24, 25 nearer to each other and increases their holding effect on the protective elements.

The protective elements are assembled in the base in the following manner: The shaft 12 of the element 11 is passed through one of the perforations in the row 22 and its shaft 13 passed through a perforation in the row 23. Then the shaft 12 of the element 11A is passed through one of the perforations in the row 23 and its shaft 13A through a perforation in the row 22 and so on, thus getting an interlocking effect between the tie portions 14, 14A of the protective elements. It will be seen that, as viewed in Fig. 3, the tie portions 14 of one of the protective elements 11 passes over the tie portion 14A of one of the elements 11A and that the tie portion 14 of the next element 11 passes under the tie portion 14A of the same element 11A. In order to get this desired effect the space between the shafts 12 and 55 13 of the elements 11, is shorter than the space

between the shafts 12 and 13A of the elements 11A. After the tie portions have been pushed up to the part 21 of the base, its sides 24, 25 may be pressed inwardly. If desired the tie portions may be covered with solder or cement as shown at 29 in Fig. 2.

This construction illustrated in Figs. 1-3 is applicable for use on narrow ledges. For wider ledges the construction illustrated in Fig. 4 is preferable. In this case the upper part 21A of the base 20A is wider and the rows of perforations therein are more widely separated. This enables the protective elements to be positioned divergently, as shown, and to thus be capable of protecting a wider space. In this case a strip 29A may be placed under the tie portions of the protective elements and riveted to the upper part 21A of the base as shown.

The base 30 of the construction illustrated in Figs. 5 and 6 is a longitudinally continuous member having an upper portion 31 and integral sides 32 and 33 extending downwardly and divergently therefrom. 34 is a longitudinal row of equally spaced holes through the transverse center of the portion 31 at right angles thereto. Similarly spaced holes 35 and 36 are provided in the sides 32 and 33 respectively intermediate the holes 34 and at right angles to these sides.

Similar protective elements 40, 40A and 40B each having shafts 41, 42 interconnected by portions 43, pass through these holes, preferably in the sequence shown. Shaft 41 of element 40 passes through one of the holes in the row 34 and its shaft 42 passes through the next adjacent hole to the right in the same row, as shown in Fig. 6. The shafts of next element 40 are similarly placed in the next two holes in the row 34 and so on.

The shaft 41 of the element 40A is placed in the hole in row 35 between the shafts 41 and 42 of element 40 and its shaft 42 in the next adjacent hole to the right in the same row. The shafts 41 and 42 of element 40B are placed in the holes in row 36 in such relative position as to bring its shaft 41 in transverse alignment with the shaft 42 of element 40A. In Fig. 5 a strap 45 is shown for securing the device to a desired structure. It has a portion which surrounds the base 30 and parallel perforated portions extending laterally from the base through which a screw 46 or the like may be passed. If desired, the connecting portions may be covered with solder or cement 29, Fig. 5.

Although the arrangement shown in Figs. 5 and 6 has a comparatively narrow base, it is capable of protecting an area of considerable width.

The longitudinal continuous base 50 in Figs. 7-10 has a flat horizontal portion 51 along one edge of which is an upstanding flange 52. It is bent back upon itself, as at 53 to form a portion 54 separated slightly from the portion 51 and substantially parallel therewith which extends toward and nearly to the flange 52. In this case each of the elements 60 has a shaft 61, looped at its upper end, as at 62 and a shorter shaft 63. The lower ends of the shafts 61 and 63 are interconnected by an integral angular portion 64 which extends laterally from the shafts and fits between the portions 51 and 54 of the base with the shafts projecting through the space between the flange 52 and the adjacent edge of the portion 54.

If it is desired to have the interconnecting portions 64 of the elements intermeshed, the con-

struction shown in Fig. 10 may be used. In this case the shafts 61, 62 are placed between the shafts 61A, 62A as shown.

In Fig. 11 a base 30 is shown, similar to that in Fig. 5. In this case the shafts of the protective elements 70, 70A, 70B, and 70C are thin resilient curved wires, each of which passes through transversely aligned and longitudinally spaced holes in the sides 32, 33 of the base. These shafts, as shown, are of different length and diverge from the base at different angles. Together they form a structure upon which birds cannot alight. The longer shaft of each element may be provided with a hooked end, as shown.

15 A body of solder or cement 29 is shown in Fig. 11 in which the parts of the protective elements between the sides of the base are embedded. Another way of interconnecting the protective elements is shown in Fig. 12 in which the longitudinally continuous base is formed of a strip 80 above the central parts of the protective elements and the parts of the protective elements under the strip 80 are embedded in the body of solder or cement 81. In this case both ends of 20 the protective elements are shown provided with loops. The materials of which the strip 80 and the body 81 are made, may be varied at will, for example, they may both be made of a plastic material. In fact, plastics may be used to form 25 the parts of the other constructions shown herein.

It is sometimes desirable to make the shafts 12 and 13 of the protective elements of thin resilient wire and their resiliency may be increased 30 by making loops 12B and 13B in them as shown in Figs. 13 and 14.

Various modifications in construction, mode of operation, method of use of an invention may 35 and do occur to others, especially after benefiting 40 from knowledge of such a disclosure as that herein presented of the principles involved, but the invention itself is not confined to the present showing.

What I claim is:

45 1. Birdproofing comprising a longitudinal integral base of sheet metal folded to form an inverted trough-like structure having a flat top provided with two transversely separated longitudinal rows of spaced perforations, inwardly 50 converging, sides depending from the edges of said top and flanges extending outwardly from the lower edges of the sides, combined with a plurality of protective elements, each having a pair of spaced substantially parallel shafts of unequal 55 lengths projecting through said perforations, with loops formed on the upper ends of the longer shafts and an integral connecting tie portion under said top, the connecting portions of adjacent elements lying diagonally across said 60 rows of perforations in opposite directions and across one another to intermesh and to position their corresponding shafts in opposite rows of perforations.

65 2. Birdproofing comprising a longitudinal continuous base of sheet metal having a flat top provided with two transversely separated longitudinal rows of spaced perforations, and sides depending from the base of said top, combined with two sets of protective elements, each element 70 having a pair of spaced substantially parallel rigid shafts of unequal lengths projecting through said perforations, and an integral connecting tie portion under said top, the connecting tie portions of one set being shorter than those of the other set, the connecting tie portions

of adjacent elements lying diagonally across said rows of perforations in opposite directions to position their corresponding shafts in opposite rows of perforations, the shorter tie forming portions lying alternately over and under a longer tie portion.

3. Birdproofing comprising a longitudinally continuous base of sheet metal folded to form an inverted trough-like structure having a top provided with two transversely separated rows of 10 perforations, inwardly converging sides depending from the edges of said top and flanges of unequal widths projecting outwardly from the lower edges of the sides with a lip extending downwardly from the outer edge of the wider flange, 15 combined with a plurality of protective elements, each having a pair of substantially parallel shafts projecting through said perforations and an integral connecting tie portion under said top, the connecting tie portions of adjacent elements lying diagonally across one another to intermesh and to position their corresponding shafts in op- 20

posite rows of perforations, the wider flange being provided with perforations between the side from which it projects and the lip at its outer edge, for the reception of fastening devices.
